UNITED STATES PATENT OFFICE.

FREDERICK H. APEL, OF ATHOL SPRINGS, NEW YORK, ASSIGNOR OF ONE-HALF TO
CHARLES W. MUNSCHAUER, OF BUFFALO, NEW YORK.

SPRING-FORKED HOLDER.

1,242,122.

Specification of Letters Patent.

Patented Oct. 9, 1917.

Application filed May 13, 1913. Serial No. 767,474.

To all whom it may concern:

Be it known that I, FREDERICK H. APEL, a citizen of the United States, residing at Athol Springs, in the county of Erie and 5 State of New York, have invented certain new and useful Improvements in Spring-Forked Holders.

The following I declare to be a full, clear and exact description of my invention, such 10 as will enable others skilled in the art to which it appertains, to make and use the same, reference being had to the accompanying drawings and to figures of reference marked thereon, which form part of this 15 specification. Like figures refer to like parts.

My invention relates to supporting means adapted to support towels and other articles.

The objects of my invention are to provide 20 useful and handy means which is self contained and can be screwed to a wall or other support for suspending articles, which can be readily attached to and detached from the same; to provide an article of 25 manufacture which can be cheaply made and which will be attractive in appearance and saleable; and to further provide a device which will not injure articles when being attached to or detached from it.

30 My holder consists of two pieces, one of which is a screw eye, the other being a piece of sheet metal formed about the said screw eye into a spring fork, illustrated in the drawings.

35 In the drawings,—

Figure 1 is a perspective view of my invention.

Fig. 2 illustrates an ordinary screw eye.

Fig. 3 is a plan of a blank cut from a 40 sheet of metal used in forming the fork.

Fig. 4 is a cross section on the line $\alpha-\alpha$, of Fig. 1.

45 Referring to Fig. 1, 1 is the screw eye having a threaded portion 2 and an eye portion 3. The threaded portion 2 passes through a hole 4 in the crotch 5 from which project the tines 6 and 7 forming the fork. A tongue 8 integral with the sheet metal forming the tines 6 and 7, passes through 50 the hole 9 and the eye 3 and is bent to bind the sheet metal to the said screw eye 1, to form a body. The respective free ends 10

and 11 of the tines 6 and 7 are bent outward.

In Fig. 2 the screw eye 1 has a threaded portion 2 and an eye 3.

In Fig. 3, the blank 12 has a hole 4, a hole 9 and a tongue 8.

In Fig. 4, the transverse curvature of the tines 6 and 7 is shown providing the convex 60 inner faces for the sides and the longitudinal edges 13, 14, 15 and 16 are turned outward.

The blank 12 shown in Fig. 3 is cut from sheet metal in a stamping machine. The 65 convexity of the tines 6 and 7 and the outward curvature of the ends 10 and 11 are formed between dies adapted for the same. After inserting the screw eye 1 in the hole 4 the tines 6 and 7 are bent together around 70 the screw eye 1 between another set of dies and are bound together by the tongue 8. The screw portion 2 is thus made an integral part of the spring forked holder which, when screwed to a wall or other support, 75 forms a very serviceable means for supporting any article pressed in between the tines 6 and 7 of the spring forked holder. Inasmuch as the edges 13, 14, 15 and 16 are turned outward, there is no danger of the 80 suspended article coming in forced contact therewith, to cut or damage the same.

On account of the tines 6 and 7 being straight for most of their length, they afford the maximum amount of gripping surface 85 for flexible articles such as towels or other cloths.

I claim,—

The combination in a supporting means, adapted for screw-threaded attachment to 90 a penetrable surface, of a threaded member and a U-shaped clamping member, said U-shaped clamping member having two closely positioned long practically parallel elastic arms with opposing convexed surfaces, with out-turned ends, the said threaded member being attached at the bend of the U of said clamping member, adapting the same to be attached to or removed from said penetrable surface.

FREDERICK H. APEL.
